UNITED STATES PATENT OFFICE.

MICHAEL J. HEIDELBERG, OF ST. LOUIS, MISSOURI.

PIPE-CLEANING DEVICE.

Application filed June 10, 1921. Serial No. 476,503.

To all whom it may concern:

Be it known that I, MICHAEL J. HEIDELBERG, a citizen of the United States, and residing at St. Louis, Missouri, have invented the new and useful Improvement in Pipe-Cleaning Devices, of which the following is a specification.

This invention relates to devices for cleaning or clearing pipes, and is more particularly adapted for cleaning waste pipes including the trap thereof.

One of the objects of this invention is to provide means for operating a wire tool in the pipe so as to quickly and effectively clear the same of obstructions.

Another object of this invention is to provide means whereby such a tool may be progressively fed into the pipe and operated while being fed.

Another object of this invention is to provide means for guiding the wire when inserting the same into the pipe and to support the wire so guided during operation.

Further objects will appear from the detail description taken in connection with the accompanying drawing, in which:

Figure 1 is a view in elevation of the device embodying this invention showing the method of inserting the tool into the pipe trap;

Figure 2 is a section on line 2—2, Figure 1;

Figure 3 is a detail sectional view of the guiding head;

Figure 4 is a detail sectional view of the chuck;

Figure 5 is an end view of Figure 4;

Figure 6 is an enlarged view of the reamer attached to the end of the wire; and

Figure 7 is an end view of Figure 6.

Referring to the accompanying drawing, Figure 1 shows a frame consisting of a top plate 1 supported by iron pipe legs 2 which are joined near their ends by a lower plate 3 adapted to brace the legs 2 and to provide a lower support for some of the operating connections as will be hereinafter described.

Mounted on the upper plate 1 in a bracket 4 is a reel 5 adapted to carry the wire 6 which is used for operating the tool. The wire 6 may be round or square or of any other suitable figure in cross-section and heavy enough to transmit the required rotary movement to the tool, but flexible enough to be easily passed through the bends of the pipe. The part of the wire 6 not in

use is wound upon the reel 5. The reel 5 is suspended by a swivel 7 from the bracket 4 in order to permit the reel to rotate in accordance with the movement of the wire. 60

Mounted in a suitable bearing in the top plate 1 is a sleeve 8 carrying at its upper end a bevel gear 9 and at its lower end below the plate 1 a spur gear 10. Movable mounted in the sleeve 8 and splined thereto 65 or otherwise suitably arranged for rotation with the sleeve 8 while permitting longitudinal movement therethrough, is a hollow shaft 11. The shaft 11 carries at its lower end a chuck 12 adapted to clutch the wire 6 which is passed through the body of the shaft 11. The shaft 11 also passes through a cross-head 13. Collars 14 and 15 fixed to the shaft above and below the cross-head prevent the shaft from sliding through the 70 cross head while permitting it to rotate therein.

The cross-head 13 is mounted to slide vertically on a pair of guide rods 16 mounted in the plates 1 and 3 and is in threaded engagement with a screw 17 vertically mounted for rotation in the plates 1 and 3. The upper end of the screw 17 is provided with a journal working in a sleeve 18 rotatably mounted in the plate 1 and carrying at its 85 lower end a gear 19 adapted to mesh with the gear 10 on the sleeve 8. The sleeve 18 also carries below the gear 19 a clutch member 20 adapted to engage another clutch member 21 fixed to the screw 17. An operating lever 22 pivotally mounted on one of the legs 2 is adapted to throw the member 21 into and out of engagement with the member 20 so as to rotate or stop the screw 17 at will. 90

The bevel gear 9 is adapted to mesh with another bevel gear 23 mounted on a shaft working in a bearing 24 on the plate 1 which shaft carries at its other end an operating crank 25. 95

The chuck 12 may be constructed in any usual manner, one form of which is illustrated in Figure 4. In this arrangement the end of the shaft 11 is threaded to engage the threaded bore of a split collar 26 between the outer split ends of which are confined a set of jaws 27 having exterior bevel surfaces adapted to engage the interior bevel surfaces of the clamping collar 28 fixed to the collar 26. The rear ends of the jaws 110 27 are adapted to abut against the end of the shaft 11 so that when the chuck is 100 105

screwed up on the shaft, the jaws 27 will be forced forward and, by engagement with the bevel surface of the clamping collar 28, will be forced inwardly to clutch the 5 wire.

In Figure 6 is illustrated a tool which may be used with this device. This comprises a tapered fluted reamer 29 which may be detachably secured to the wire 6 by means 10 of a chuck 30 or other suitable means.

Usually the most easily accessible opening of a waste pipe is the trap 31 shown in Figure 1. When such a trap is located below the surface of the ground access is 15 usually obtained thereto through a pipe connection 32 extending to the surface. In order to guide the wire in this part of the pipe, a pipe or conduit 33 is provided adapted to extend into the trap 31 and having a bent end 34 adapted to guide the wire around the lower curve of the trap. The conduit 33 may be provided with guiding heads at both ends adapted to guide and centralize the wire in the conduit. These 20 heads may be constructed as shown in Figure 3. A cylindrical plug 35 is arranged to be fixed in the end of the conduit 33 as by means of the set-screw 36. This plug has a tapered bore 37 adapted to guide the 25 wire through the central opening 38 in the end thereof. The plug 35 has a reduced portion adapted to fit loosely into a cup 39 which is in turn adapted to fit loosely within the conduit 33. The cup 39 is removably attached to the plug 35 by means of a circular spring wire 40 which is snapped into a pair of corresponding grooves in the interior surface of the cup 39 and the exterior surface of the plug 35, as shown in 30 Figure 3. By this arrangement the cup 39, which has a central opening 41 through which the wire 6 passes, is permitted to rotate on the plug 35 with the rotation of the wire 6.

45 In using this device the wire leaving the reel 5 is passed through the bore of the shaft 11 thence through a guide bushing 42 in the bottom plate 3 and is then passed through the conduit 33, after which the 50 reamer 29 or other suitable tool is attached to the end thereof. The conduit 33 is then inserted into the pipe so that the bent end 34 will follow the bend of the trap 31. The frame of the machine is then placed 55 over the pipe 32 in such a way that the wire will feed properly from the bushing 42 into the conduit 33. The cross-head 13 having been worked to its topmost position, the chuck 12 is operated to clutch the wire. 60

65 The operator now turns the crank 25 which by means of the gears 23 and 9 will rotate the shaft which in turn will rotate the wire 6 so as to rotate the tool 29 in the pipe. Rotation of the gear 9 will also rotate the gear 10 on the lower end of the

sleeve 8. The gear 10 will drive the gear 19 with which it meshes. The operator may now work the handle 22 to throw the clutch member 21 into cooperation with the member 20 so as to rotate the screw 17. Rotation of the screw 17 will now feed the cross-head 13 downward so as to feed the wire in to the pipe. When the wire has advanced into the pipe a distance corresponding to the travel of the cross-head 13, 75 the chuck 12 may be loosened and the cross-head retracted by reversing the rotation of the crank 25.

It will, therefore, be seen that a very convenient and effective device for clearing 80 pipes is hereby provided. Operation of the crank 25 will not only rotate the chuck 12 so as to rotate the tool in the pipe but will also, when the clutch member 21 has been thrown into engagement with the member 20, operate to feed the tool into the pipe, and these two operations may be carried on simultaneously or the feed may be interrupted at the will of the operator. It 85 will be noted that a means for positively 90 feeding or projecting the wire into the pipe and against obstructions are provided. The wire is guided through a great part of its length or until it arrives at such a point where no guiding means can be further inserted. The combined rotary and feeding movement of the tool are effective in disintegrating the material of whatever obstructions may be encountered so that the same 95 may subsequently be flushed out. During 100 all of the operations, the wire feeds freely from the reel 5 and this reel can rotate freely on the swivel 7 in accordance with the rotation of the shaft 11.

It is obvious that various changes may 105 be made in details of construction without departing from the spirit of this invention; it is, therefore, to be understood that this invention is not to be limited to the specific details shown and described.

Having thus described the invention, what 110 is claimed is:

1. A pipe cleaning device employing a wire tool, comprising, a frame, a chuck mounted for movement on said frame, means for guiding the wire to said chuck, said chuck being adapted to clutch the wire at various points therealong, and means for operating said chuck in order to work the 115 tool in the pipe.

2. A pipe cleaning device employing a wire tool, comprising, a frame, a chuck mounted for movement on said frame, means for guiding the wire to said chuck, said chuck being adapted to clutch the wire at various points therealong, and means for operating said chuck adapted to rotate the 120 tool in the pipe.

3. A pipe cleaning device employing a wire tool, comprising, a frame, a chuck 125

- mounted for movement on said frame, means for guiding the wire to said chuck, said chuck being adapted to clutch the wire at various points therealong, and means for operating said chuck adapted to project the tool into the pipe and to rotate the tool therein. 65
4. A pipe cleaning device employing a wire tool, comprising, a frame, a chuck mounted for movement on said frame and adapted to clutch the wire, a reel for the wire, and means for operating said chuck adapted to feed the wire from said reel and into the pipe. 10
5. A pipe clearing device employing a wire tool, comprising, a frame, a chuck mounted for movement on said frame and adapted to clutch the wire, a reel for the wire swiveled on said frame, and means for operating said chuck to rotate the tool in the pipe. 15
6. A pipe cleaning device employing a wire tool, comprising, a frame, a chuck mounted for movement on said frame and adapted to clutch the wire, a reel for the wire, means for operating said chuck to rotate the tool in the pipe, and means adapted to permit rotation of said reel in accordance with the rotation of the tool. 20
7. A pipe cleaning device employing a wire tool, comprising, a frame, a chuck mounted for movement on said frame and adapted to clutch the wire, means for operating said chuck to rotate the tool in the pipe and a movable cross-head adapted to feed the tool. 25
8. A pipe cleaning device employing a wire tool, comprising, a frame, a chuck mounted for movement on said frame and adapted to clutch the wire, a movable cross-head adapted to movably support said chuck, and driving means adapted to rotate the tool and to move said cross-head to feed the tool. 30
9. A pipe cleaning device employing a wire tool, comprising, a frame, a chuck mounted for movement on said frame and adapted to clutch the wire, a movable cross-head adapted to movably support said chuck, driving means adapted to rotate the tool and to move said cross-head to feed the tool, and means for interrupting the feed of the tool. 35
10. A pipe cleaning device employing a wire tool, comprising, a frame, a chuck mounted for movement on said frame and adapted to clutch the wire, a movable cross-head adapted to movably support said chuck, driving means adapted to rotate the tool and to move said cross-head to feed the tool, and a releasable clutch between said cross-head and said driving means. 40
11. In a pipe cleaning device employing a wire tool, a conduit adapted to enter the pipe, and means for guiding the wire for movement along said conduit. 45
12. In a pipe cleaning device employing a wire tool, a conduit adapted to enter the pipe, having a part adapted to enter a trap, and means for guiding the wire for movement along said conduit. 50
13. In a pipe cleaning device employing a wire tool, a conduit adapted to enter the pipe having a bent portion, and means for guiding the wire for movement along said conduit. 55
14. In a pipe cleaning device employing a wire tool, a conduit adapted to enter the pipe and along which the wire is moved, and means at an end of said conduit adapted to guide the issuing wire into and along the pipe. 60
15. In a pipe cleaning device employing a wire tool, a conduit adapted to enter the pipe and along which the wire is moved, and guiding means at each end of said conduit. 65
16. In a pipe cleaning device employing a wire tool, a conduit adapted to enter the pipe and along which the wire is moved, and guiding means at one end of said conduit adapted to center the wire therein. 70
17. A pipe cleaning device employing a wire tool, comprising, a frame, a chuck mounted for movement on said frame and adapted to clutch the wire, a conduit adapted to enter the pipe, means for guiding the wire in said conduit, and means for operating said chuck in order to work the tool in the pipe. 75
18. In the art of clearing pipes of obstructions, the process comprising, inserting the working end of a stiff wire into the pipe while the trailing end is reeled, and feeding the working end along the pipe while the reeled part is rotated. 80
19. In the art of clearing pipes of obstructions, the process comprising, inserting the working end of a stiff wire into the pipe while the trailing end is reeled, rotating the wire and the reeled part, and feeding the working end along the pipe while the reeled part is unwound. 85
20. A device for clearing pipes of obstructions comprising, a plain stiff wire having a working tool at one end and having the trailing end thereof reeled, said wire and its reeled part being adapted for rotation and unwinding as said tool is fed along the pipe. 90
21. A device for clearing pipes of obstructions comprising, a wire having a working tool at one end and having the trailing end thereof reeled, and means for rotating said wire and its reeled part and for feeding said tool along the pipe. 95

In testimony whereof I affix my signature this 17th day of May, 1921.

MICHAEL J. HEIDELBERG.
